CENTRIFUGAL FAN

Myron W. Buchanan, Short Hills, N. J., assignor
to The Singer Manufacturing Company, Elizabeth, N. J., a corporation of New Jersey

Application December 5, 1941; Serial No. 421,701

3 Claims. (Cl. 230—114)

This invention relates to fans and more particularly to fans of the centrifugal type and has for its principal objective the provision of improved means for feathering the blades of the impeller so that the output of the fan may be regulated independently of the speed thereof.

Another object of this invention is to provide means for simultaneously adjusting all of the blades the same amount and for simultaneously locking the blades in their adjusted position.

Another object of this invention is to provide improved means for varying the amount of air delivered by the fan so that a single type of fan can be used to meet various specifications and requirements thereby reducing the number of fans of various air delivery capacities that have to be kept in stock.

A further object of this invention is to provide a simple, easy and effective mechanism for varying the output of the fan without in any way restricting or obstructing the inlet opening of the fan and to provide improved means for cooling the fan motor.

A still further object of this invention is to provide improved means for adjusting the angle of the impeller blades which is easily and readily accessible and in which the adjustment can be made without disturbing the permanent installation of the fan and its actuating motor.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings Fig. 1 is an end elevation of the fan or blower, showing the intake orifice or inlet end of the fan.

Fig. 2 is a vertical section taken along the line 2—2 of Fig. 1.

Fig. 3 is a section taken along the line 3—3 of Fig. 2.

Fig. 4 is a face view of the disk which carries the impeller blades.

In the embodiment selected for illustration 10 represents a square shaped casing made of sheet-metal, or any other suitable material, and reinforced with angle-bars 11 at its edges and through its central portion. Opposite sidewalls of the casing 10 are provided with aligned circular openings 10a. The casing is provided with an exhaust or outlet 12, which is also con-

nected with the scroll 13, and readily removable inspection doors 14 are provided on opposite sides of the casing for the purpose of inspection and cleaning. Fixed to each side of the casing 10 by the screws 15, and surrounding one of the openings 10a, is a flat ring 16 and welded to the ring and casing is a circular member 17 having an L-shaped cross-section. From the above, it will be understood that as the edges of the casing 10 are equal in length and are disposed at 90° relative to each other, the fan outlet may be arranged to discharge at any of four positions, and as the sides are symmetrical the fan motor may be removably secured to either of the members 17 to project through either of the openings 10a in the casing thus providing eight different positions in which the discharge outlet may be placed.

Removably secured to a selected one of the circular members 17 by the bolts 19 is a motor supporting plate 20 which forms one of the end bonnets for the motor and has removably secured thereto an inspection plate 18. Secured to the plate 20 by the bolts 21 is a casing 22 which carries the stator 23 and the end bonnet 24 of the motor. A motor shaft 25 carrying a rotor 26 is journaled in suitable bearings 27 and 28 carried by the supporting member 20 and the end bonnet 24. Secured to the extending end 25 of the motor shaft 25, for rotation therewith, is a disk 30 formed with a hub 29, strengthening ribs 31 and bearing bosses 32 which are arranged near the outer periphery of the disk and are equally spaced from each other.

Journaled in and extending through each of the bearing bosses 32 is one end of a shaft 33 having a fan-blade 34 rigidly fixed thereto and the other end of each of the shafts 33 is held in a ring 35, the purpose of which is to hold the blade supporting shafts in parallelism.

Removably secured to that one of the rings 16 which is at that side of the casing remote from the motor, is a sheet metal air-funnel 50 which directs air into the casing within the path of rotation of the fan blades.

Fixed to the end of each of the shafts 33 which extends through the boss 32, and at the side opposite the blade 34, is a gear 37. All of the gears 37 mesh with a large or main gear 38 journaled on the hub 29 of the disk 30. The gear 38 is adapted to be moved about the hub 29 and is provided with two arcuate slots 40 through each of which a locking screw 41 passes, the screw being received by one of the threaded bosses 42 formed on the disk 30.

From the foregoing it will be observed that access to the impeller may be had by removing the inspection plate 18 and through the opening the locking screws 41 may be loosened and the gear 38 moved about the hub 29 as an axis until the blades 34 assume the desired position. The screws 41 may then be tightened to lock the gear 38, and as the gears 37 mesh with the gear 38 the gears 37 and blades 34 are also locked in the desired position.

The disk 30, near its outer periphery and adjacent the bearing bosses 32, is formed with strengthening ribs 44 which, together with the strengthening ribs 31 form a centrifugal fan which draws air through the screened intake 45 in the end bonnet 24 of the motor, the screened outlet 46 in the plate 20 through the openings 47, Fig. 3, formed in the large gear 38 and is then forced into the fan exhaust 12. This arrangement provides means for cooling the motor when the fan is operating.

From the foregoing description it will be observed that I have constructed a centrifugal fan in which a single means is provided for adjusting the impeller blades to thereby regulate the volume of air delivered or the static pressure produced by the fan, and this adjustment may be made before or after the fan has been installed. It will be understood that after the screws 41 have been loosened the large gear 38 may be adjusted by turning any of the small gears 37 or any of the shafts 33 to which the gears 37 are fixed, thereby adjusting all of the blades simultaneously. It is apparent that such a construction has a wide variety of uses, and it will be understood that the form, and arrangement of the elements employed may be varied. Therefore, the privilege is reserved of resorting to all such legitimate changes therein as may be fairly embodied within the spirit and scope of the appended claims.

Having thus set forth the nature of the invention what I claim herein is:

1. In a centrifugal fan, in combination, a casing provided with a circular opening; a circular member, substantially L-shape in cross section, secured to the outside of said casing around said opening; a fan-driving motor having at one end an annular flange secured to said circular member with the shaft of the motor extending through said opening and into said casing; a circular disk located within said casing and having a hub secured to said motor shaft; a plurality of bearing bosses carried by said disk adjacent its outer periphery, each of said bosses being provided with a cylindrical bearing having its axis parallel with the axis of the motor shaft; a metal ring spaced from said disk and affording a plurality of bearings each complementary to and aligned with one of the bearings provided by said disk; a plurality of fan blades each having a shaft journaled in two of said aligned bearings; a relatively large main gear journaled on the hub of said disk for limited angular adjustment; and a relatively small gear secured to one end of the

shaft of each fan blade and meshing with said main gear, whereby angular adjustment of said main gear effects greater angular adjustment of all of said fan blades.

5. In a centrifugal fan, in combination, a box-like casing having aligned openings in its opposite sidewalls; a pair of circular members, substantially L-shaped in cross section, one of which is secured to each of said sidewalls around one of said openings; a fan-driving motor having at one end an annular flange adapted to be secured to either of said circular members so that the shaft of the motor will extend through the adjacent opening and into the casing; a circular disk having a hub secured upon the end of said motor shaft within said casing, said disk being adjacent to and substantially closing one of the openings in the casing; a plurality of bearing bosses provided by said disk adjacent its periphery; a plurality of fan blades each having a shaft journaled in one of said bearing bosses; a relatively small gear secured upon each of said fan shafts; a relatively large main gear journaled on the hub of said disk for limited angular adjustment and meshing with all of the gears on said fan shafts, whereby angular adjustment of said main gear effects greater angular adjustment of all of said fan blades; and means to lock said main gear to said disk in its various positions of adjustment.

3. In a centrifugal fan, in combination, a casing having aligned circular openings in its opposite sidewalls; a pair of circular members, angular in cross section, of which one is secured to each of said sidewalls around one of said openings; a fan-driving motor secured to one of said members and having its shaft extending into said casing; a ring secured to said casing within the other of said members, an air-funnel secured to said ring and projecting into said casing for directing air thereinto; a fan-blade-carrying disk secured upon said motor shaft within said casing and adjacent one of said openings; a pair of threaded bosses carried by said disk; a plurality of fan-blade-supporting shafts each having one end rotatably carried by said disk with their axes parallel to the axis of said motor shaft; a fan-blade carried by each of said fan-blade-carrying shafts; means adjacent the other of said openings and engaging said fan-blade-carrying shafts to hold said shafts and fan blades against relative lateral movement; a relatively small gear secured upon each of said fan-blade shafts; a relatively large main gear journaled coaxial with said motor shaft and meshing with each of the gears on said fan-blade shafts, whereby angular adjustment of said main gear simultaneously effects greater angular adjustment of all of said fan blades; said main gear being provided with a pair of arcuate slots; and a clamp-bolt passing through each of said slots and threaded into one of the threaded bosses on said disk to lock said main gear in its various positions of adjustment.

65 MYRON W. BUCHANAN.
